(57) **CLAIM**

The ornamental design for a drink flask cap insert, as shown and described.

DESCRIPTION

FIG. 1 is a perspective view from above and to the left of the invention;

FIG. 2 is a perspective view from below and to the right of the invention;

FIG. 3 is a left-side elevational view of the invention;

FIG. 4 is a back-side elevational view of the invention; and,

FIG. 5 is a bottom view of the invention.

As shown at <http://vimeo.com/16461385>, the instant invention is an insert that fits in a cap for a sports bottle or flask. The insert projects upward from the cap and seals a chamber that is formed in the cap and downwardly closed by a metal foil. This chamber holds a flavored syrup, and the cap is intended to be mounted on the threaded neck of a bottle filled with water. Pushing the insert down pierces the metal foil and releases the syrup into the water.
